[57] CLAIM

The ornamental design for a speaker enclosure, as shown and described.

DESCRIPTION

FIG. 1 is a front view of the speaker enclosure showing my new design;

FIG. 2 is a left side view of the speaker enclosure showing my new design, the right side view being a reverse image thereof;

FIG. 3 is a rear view of the speaker enclosure showing my new design;

FIG. 4 is a top view of the speaker enclosure, the bottom view being a reverse image thereof;

FIG. 5 is a perspective view of the speaker enclosure;

FIG. 6 is a front view of an alternate embodiment of FIG. 1; and,

FIG. 7 is a perspective view of FIG. 6.

The sides, rear, top and bottom views of the embodiment disclosed in FIG. 6 are identical to FIGS. 2-4.
